[57] CLAIM

The ornamental design for a two-way marine radio or
similar article, substantially as shown and described.

DESCRIPTION

FIG. 1 is a front, top and right side perspective view of
a two-way marine radio or similar article showing my
new design;

FIG. 2 is a left side elevational view;

FIG. 3 is a bottom plan view;

FIG. 4 is a rear elevational view; and

FIG. 5 is a view similar to FIG. 1 of a modified form of
the radio, wherein the leftmost front channel selector
knob is replaced with a light emitting diode display and
there are seven instead of four pushbuttons.U.S. Patent
